METHOD OF AND APPARATUS FOR APPLYING CLOSURE CAPS TO RECEPTACLES

Ernst von Segebaden, Drottningholm, and Bror Johnson, Alsten, Sweden, assignors to Aktiebolaget Gerh. Arehns Mekaniska Verkstad, Stockholm, Sweden, a corporation of Sweden

Application October 31, 1934, Serial No. 750,890
In Sweden November 4, 1933

14 Claims. (Cl. 226—87)

This invention relates to an improved method and apparatus for applying closure caps to jars, bottles or similar receptacles.

One object of our invention is to provide a simple method of and apparatus for applying closure caps to jars, bottles or similar receptacles, forcing the material of the cap into intimate contact with the neck of the receptacle, conforming said material in accurate accordance with exterior beads, threads or irregularities of the neck of the receptacle.

Another object of our invention is to provide a method of and apparatus for applying closure caps to jars, bottles or similar receptacles, exerting a sufficient downward pull upon the skirt of the cap to maintain an hermetic seal without exerting undue pressure, tending to injuriously affect the top of the cap and a gasket or the like applied between the mouth of the receptacle and the top of the cap.

Still another object of our invention is to provide a method of and apparatus for applying closure caps to jars, bottles or similar receptacles, to accommodate at all times the capping elements employed to the external surface of the part of the receptacle to force the material of the receptacle into intimate contact with said contour regardless of the shape of said contour which may have irregularities, deformations or threads, at all times maintaining a uniform downward dragging action upon the material of the cap skirt that is to be brought into conformity with the contour of the underlying part of the receptacle, avoiding undue deformations of the parts of the skirt to be applied.

Still another object of our invention is to provide a method of and apparatus for spinning closure caps to the threaded necks of jars, bottles or similar receptacles, to continuously pull the material of the closure cap downwardly from the top of the receptacle, exerting a uniform dragging action independently of the spinning action.

Still another object of our invention is to provide a method of and apparatus for applying closure caps to preferably threaded necks of jars, bottles or similar receptacles, progressively forcing one part of the cap into intimate conformity with the threads or the like on simultaneously bending and securing a lower sealing portion of the cap below a rim or the like of the neck of the receptacle, utilizing practically all the period of cap applying for firmly securing said sealing portion.

The invention will hereinafter be described by way of examples with reference to the accom-

panying drawings, in which similar reference characters are used to designate corresponding parts throughout the several views:—

Fig. 1 is a vertical sectional view of the apparatus, with the parts in the relative positions which they assume prior to the bringing of the receptacle into position to initiate the cap applying operation; Fig. 2 is a similar view, showing the relative positions which the parts assume after the receptacle has been elevated into operative position, the cap applying operation having been completed; Fig. 3 is a vertical sectional view of another embodiment of the apparatus; Fig. 4 is a vertical sectional view of part of the apparatus, forming still another embodiment of the invention; Fig. 5 is a vertical sectional view of the lower part of still another embodiment of the apparatus as well as the neck of a receptacle, the operative parts of the apparatus having finished the cap applying; Fig. 6 is a section on the line VI—VI of Fig. 3; Fig. 7 is a section on the line VII—VII of Fig. 3. Figs. 8 to 11 show modified embodiments of the invention.

Referring to the drawings, 1 designates a casing enclosing a spinning head. To the upper hub portion 55 of the casing is secured a cap 2 and in its lower end is secured a bell 3 having a central opening 56. A sleeve 57 forms an extension of a gear wheel 4 and is rotatably journaled within the hub 55 and meshes with another gear wheel 5 part of which is shown in the drawings. A nut 62 is threaded to the top end of the sleeve 57 and a wear ring 63 is interposed between the nut 62 and the top end of the hub 55 thus suspending the gear wheel 4. The wheel 5 is mounted on a continuously driving shaft, not shown. A sleeve 6 is fitted within the sleeve 57 and mounted for longitudinal movement therein. Relative rotary movement between the gear wheel 4 and the sleeve 6 is prevented by a key 8 fitting neatly within a recess in the sleeve 6 and extending freely within an elongated slot 7 formed upon the inner surface of the sleeve 57 and gear wheel 4. Secured to the lower extremity of the sleeve 6 is a plate 19, integrally formed with four depending spaced fingers 10 for guiding the bottle neck when the latter is elevated into operative position. A longitudinally movable, non-rotatable shaft 11 is fitted within the sleeve 6. One end of a coiled contractile spring 12 is interposed between the cap 2 and a ring 9 secured to the shaft 11 so that the spring will force the shaft downwards and hold a ring 65 secured to the shaft 11 in abutting relation to a hub 66 on the cap 2 to suspend the capping mechanism.

The lower extremity of the shaft 11 has a radial flange 13 fitting within a recess 14 forming an extension of the central bore of the sleeve 6. Moreover, the lower extremity of the shaft 11 has a central bore 15 in which is longitudinally movable a pin 16 forming an upper extension of a plunger 17 which serves as an abutment for the bottle to be capped. A coiled contractile spring 18 seats upon an abutment of the bore 15 as well as upon a radial flange 58 of the plunger 17 and serves to hold with yielding pressure the flange 58 against the plate 19. Four radial brackets 59 are formed integrally with the sleeve 6. To the brackets there are pivoted two levers 22 and two levers 61. The upper extremity of each lever carries an anti-friction roller 27 and a weight 26. The rollers 27 are mounted to roll upon the substantially conical inner surface 64 of an annular trackway 28 secured to the casing 1. Each lever 22 is arranged opposite to a lever arm 61.

On the extremity of the depending arms of each lever 61 is rotatably journalled a spinning disc 20. To the depending arms of the levers 22 are pivoted links 23 having a rear extension 82 and being connected to one end of a tension spring 24, the other end of which is secured to a corresponding finger 10. The springs 24 urge the links 23 to swing downwards to force the extensions 82 to engage abutments 25 on the levers 22. Each link 23 carries a spinning disc 21 which is rotatably journalled thereon and the spinning face of which is shaped like the groove of the receptacle thread. When rotating the sleeve 6 with the arms 22 and 61, centrifugal force will fling the weights 26 outwardly and the several parts will occupy the position shown in Fig. 2 so that the discs 20 and 21, respectively, are movable to different levels and transversally to the receptacle 29, the discs 21 occupying a higher position than the discs 20. The discs 20 are positioned somewhat nearer the longitudinal axis of the spinning mechanism than the discs 21.

In operation, a cap 30 is placed on the threaded neck of the bottle 29 which is then elevated from its initial position shown in Fig. 1 to abutting engagement with the plunger 17. The continuously rotating gear wheel 5 revolves the gear wheel 4 which drives the sleeve 6 to rotate with the arms 22 and 61 with the spinning discs and the weights. Thereby, the anti-friction rollers 27 are pressed against the lower part of the surface 64 of the trackway 28 by the weights 26 and all the spinning discs are still held out of engagement with the cap on the bottle neck. Continued upward movement of the bottle will first raise the plunger 17 against the tension of spring 18 to bring the flange 58 into engagement with the flange 13, and on still further continued upward movement of the receptacle the rotating sleeve 6 with the arms 22 and 61 is caused to move upwards against pressing action of the spring 12 and the rollers 27 are continuously caused to roll upon an upper wider portion of the trackway 28, and then the spinning discs are moved into engagement with the skirt of the cap covering the threaded bottle neck. Due to the fact that the discs 20 occupy an initial position less remote from the longitudinal axis of the spinning mechanism than the discs 21 the discs 20 will first hit the cap and they will bend the lower edge of the skirt of the cap below an annular rim on the bottle neck and the friction between the discs and the skirt will cause the discs to revolve during their planetary motion around the bottle neck on continuously exerting

yielding pressure upon the skirt. Immediately after the discs 20 having thus been brought into operation the discs 21 hit the skirt of the cap slightly above the inwardly bent portion thereof and force the material of the skirt into intimate contact with the thread beginning there and extending upwards towards the end of the bottle neck. Then the spinning discs are urged upwards by the groove of the thread on tensioning the springs 24. On the progressive upward movement of the discs 21 the discs 20 will constantly exert spinning action upon the lower edge of the skirt holding it with yielding pressure against the bottle neck, and permit just as much longitudinal displacement of the material of the skirt as will be necessary to allow accurate conforming of said material to the threaded portion of the bottle neck. The deformation of the skirt of the receptacle will, therefore, cause practically no changes of the initial pressure between the top of the cap and the mouth of the receptacle or upon a gasket interposed therebetween, and nevertheless the material of the cap skirt will be brought into intimate contact with practically any irregularities or deformations of the threaded portion of the bottle neck. After completing the spinning action now described the different spinning discs occupy the relative positions shown in Fig. 2. On descending the capped bottle the compressed spring 12 urges the revolving spinning mechanism downwards, the anti-friction rollers 27 will ride upon a narrower portion of the trackway and the levers 22 and 61 will swing the discs 21 and 20, respectively, out of engagement with the cap, the discs 21 in advance of the discs 20.

The embodiments illustrated in Figs. 3, 4 and 6, are developed mainly in the same manner as the one now described. According to Figs. 3 and 7, the spinning discs 20 are rotatably journalled on arms 33 secured to vertical rock shafts 34 which are journalled in radially projecting brackets 35 formed integrally with the sleeve 6. On the upper extremity of each rock shaft there is rotatably mounted a sleeve 41 having two arms 36 and 37, respectively. The arms 36 each carries an anti-friction roller 38 and the arms 37 are connected with the sleeve 6 by the intermediary of a tension spring 39. The tension spring 39 forces the roller 38 against the outer conical surface of an annular trackway 40 which is secured to the gear-wheel 4. The lower end of the sleeve 41 has a recess 42 into which projects a lug 43 from a flange 44 secured to the shaft 34. The recess has such a width that the sleeve 41 may swing freely on the shaft 34 through a certain angle. The discs 21 are according to Fig. 3 journalled on up and down swinging arms 46 which are pivoted to forks 47 on shafts 34 and actuated by springs 45, one end of which is secured to said arm, the other end being secured to a bracket 35. Each disc 20 is journalled on an arm 33 rigidly secured to a rock shaft 34. Each shaft 34 is enclosed by a spring 32 which urges the arms 33 and 46 inwards.

In operation, on pressing the plunger 17 and sleeve 6 upwards by means of the bottle 29 the arms 36 are swung inwards by the springs 39 and then the lugs 43, which engage each a side wall of a recess 42, are permitted to follow the swinging movement of the sleeves 41 and the springs 32 swing the arms 33 and 46 to yieldingly press the rollers 20 and 21, respectively, against

a cap placed on the neck of the bottle. In this case the spinning discs 21 are brought into engagement with the cap in the proximity of the mouth of the bottle and the spinning is effected 5 on downward movement of the discs 21, i. e., on tensioning the spring 45. On descending the bottle after the spinning operation has been finished the spring 12 urges the sleeve 6 and the rollers 38 downwards and the conical surface of 10 the trackway 40 forces the arms 36 outwardly, one wall of the recess 42 hits the lug 43 and the rock shafts 34 are swung back to their initial 15 angular position, i. e., the spinning discs are moved out of engagement with the cap on the bottle neck.

According to Fig. 4, the discs 21 are supported by arms 55 keyed to rock shafts 34. The forked ends of the arms 55 have vertical spindles 54 on which the discs 21 are loosely mounted. Springs 20 48 are interposed between the discs 21 and the lower legs of the forks for resiliently urging the discs upwardly. Thus the spinning discs may be urged by the engagement with threads be forced downwards on compressing the springs 48. 25 It is provided that the apparatus indicated in Fig. 5 has spring-actuated arms 22 and 61 for supporting the discs 21 and 69, respectively. Thus said arms are urged inwardly by the springs 49, one end of which is connected to the 30 arms, their other ends being connected to the sleeve 6. The spinning discs 21 are secured to shafts 50 which are rotatably journaled and axially movable in the forked ends of the arms 22. Their operative movement axially of the bottle 35 neck is effected by the thread of the bottle neck. The spinning discs 69 which have to force part of the cap skirt into an angular groove 31 of the bottle neck are loosely mounted on fixed shafts 51 in the forked ends of the arms 61 and actuated 40 at their upper side as well as at their lower side by compressed springs 52, permitting movements of the discs 69 axially of the bottle neck to conform with the groove 31, whatever irregular shape or position said groove might have.

45 According to Fig. 8, the spinning tools are developed to conform with bottle necks or the like being particularly irregularly shaped. The upper spinning tool is in this case shaped as a ring 68 loosely mounted on a spindle 53 on the 50 arm 22.

With a view of accurately adjusting the spinning discs relative to threads on the bottle necks said discs are according to Fig. 9 arranged obliquely. They are each keyed to a spindle 67 axially movable mainly in the same manner as the 55 spindle 50 of Fig. 5 but obliquely of the bottle neck in conformity with the pitch of the thread.

If desired, the cap applying tools may according to Fig. 10 instead of being rotatable discs have the shape of sliding pressing members, such as fingers 70 and 71 replacing the discs 21 and 69, respectively, shown in Fig. 5. The rear ends of said fingers straddle the arms supporting them 60 and thereby relative rotary movement is prevented. The discs 20 may possibly be replaced by pressing members, e. g., forming jaws. According to Fig. 11, two jaws 72 of rubber are supported by rotatable arms 73 arranged to be swung in 65 the same manner as the arms 22 and 61, shown in Fig. 5. Another arm 74 carries a spinning disc 75 and is arranged to rotate around the bottle neck to effect the spinning operation in the same manner as described with reference to 70 Fig. 5.

We claim:

1. Apparatus for applying a closure cap having a depending skirt to the mouth of a receptacle, comprising capping tools, said tools being singly mounted for movements at substantially different levels transversely to the receptacle to yieldingly press different longitudinal sections of the skirt against said receptacle, one of said tools being operative to move progressively longitudinally of the receptacle relative to another of said tools through a range of action beyond that of said other tool, the transverse and longitudinal movements of said one tool being independent of any other of said capping tools, and accommodating to the contour of said receptacle to force the material of the skirt into intimate contact with said receptacle. 15

2. Apparatus for applying a closure cap having a depending skirt to the mouth of a receptacle, comprising capping tools, a yielding member for 20 actuating one of said tools, said tools being singly mounted for movements at substantially different levels transversely to the receptacle to yieldingly press different longitudinal sections of the skirt against said receptacle, one of said tools 25 being operative to move progressively against the action of said yielding member longitudinally of the receptacle relative to another of said tools through a range of action beyond that of said other tool, the transverse and longitudinal movements of said one tool being independent of any 30 other of said capping tools, and accommodating to the contour of said receptacle to force the material of the skirt into intimate contact with said receptacle. 35

3. Apparatus for applying closure caps having depending skirts to the mouths of receptacles, comprising capping tools, said tools being singly mounted for movements at substantially different levels transversely to the receptacle to 40 yieldingly press different longitudinal sections of the skirt against said receptacle, one of said tools being developed as a spinning tool and operative to move progressively longitudinally of the receptacle relative to another of said tools through a 45 range of action beyond that of said other tool, the transverse and longitudinal movements of said tool being independent of any other of said capping tools, and accommodating to the contour of said receptacle to force the material of the skirt into intimate contact with said receptacle. 50

4. Apparatus for applying closure caps having depending skirts to the mouths of receptacles, comprising spinning tools, said tools being singly 55 mounted for movements at substantially different levels transversely to the receptacle to yieldingly press different longitudinal sections of the skirt against said receptacle, one of said tools being operative to move progressively longitudinally of the receptacle relative to another of said tools through a range of action beyond that of said other tool, the transverse and longitudinal movements of said one tool being independent of any other of said spinning tools, and accommodating to the contour of said receptacle to force the material of the skirt into intimate contact with said receptacle. 60

5. Apparatus for applying closure caps having depending skirts to the mouths of receptacles, comprising capping tools, said tools being singly mounted for movements at substantially different levels transversely to the receptacle to yieldingly press different longitudinal sections of the skirt against said receptacle, one of said tools 70

being operative to move progressively longitudinally of the receptacle relative to another of said tools through a range of action beyond that of said other tool, the transverse and longitudinal movements of said one tool being independent of any other of said capping tools, and accommodating to the contour of said receptacle to force the material of the skirt into intimate contact with said receptacle, said tools being mounted to actuate opposite sides of the skirt.

6. Apparatus for applying closure caps having depending skirts to the mouths of receptacles, comprising capping tools, a shaft, said tools being singly mounted for movements at substantially different levels transversely to the receptacle to yieldingly press different longitudinal sections of the skirt against said receptacle, one of said tools being developed as a spinning tool and rigidly secured to said shaft, said shaft being mounted for progressive axial movement longitudinally of and lateral movements transversely to the receptacle to move the tool secured thereto transversely and longitudinally independently of any other of said capping tools to force the material of the skirt into intimate contact with said receptacle.

7. In an apparatus for applying a closure cap having a depending skirt to the mouth of a receptacle, a pair of capping tools, a shaft, said tools being mounted for movements at substantially different levels transversely to the receptacle independently of one another to yieldingly press different longitudinal sections of the skirt against said receptacle, one of said tools being developed as a ring loosely mounted to adjust itself obliquely on said shaft and free to move longitudinally of the receptacle to progressively force the material of the skirt into intimate contact with said receptacle.

8. Apparatus for applying a closure cap having a depending skirt to the mouth of a receptacle, comprising capping tools, movable yielding carriers for said tools, said carriers supporting said tools singly to move them at substantially different levels transversely to the receptacle to yieldingly press different longitudinal sections of the skirt against said receptacle, one of said tools being operative to move progressively longitudinally of the receptacle relative to another of said tools through a range of action beyond that of said other tool, the transverse and longitudinal movements of said one tool being independent of any other of said capping tools, and accommodating to the contour of said receptacle to force the material of the skirt into intimate contact with said receptacle.

9. In an apparatus for applying a closure cap having a depending skirt to the mouth of a receptacle, capping tools, a movable carrier, said tools being singly mounted for movements at substantially different levels transversely to the receptacle to yieldingly press different longitudinal sections of the skirt against said receptacle, one of said tools being supported by said carrier to be progressively moved longitudinally of the receptacle relative to another of said tools through a range of action beyond that of said other tool, the transverse and longitudinal movements of said one tool being independent of any other of said capping tools to force the material of the skirt into intimate contact with the receptacle.

10. In an apparatus for applying a closure

cap having a depending skirt to the mouth of a receptacle, capping tools, said tools being singly mounted for movements in substantially different levels transversely to the receptacle to yieldingly press different longitudinal sections of the skirt against said receptacle, one of said tools being operative to move progressively longitudinally of the receptacle in a direction from the range of action of another of said tools towards the mouth of the receptacle, the transverse and longitudinal movements of said tool being independent of any other of said capping tools, and accommodating to the contour of said receptacle to force the material of the skirt into intimate contact with said receptacle.

11. In an apparatus for applying a closure cap having a depending skirt to the mouth of a receptacle, spinning tools, said tools being singly mounted for movements in substantially different levels transversely to the receptacle to yieldingly press different longitudinal sections of the skirt against said receptacle, one of said tools being operative to move progressively longitudinally of the receptacle in a direction from the range of action of another of said tools towards the mouth of the receptacle, the transverse and longitudinal movements of said one tool being independent of any other of said spinning tools, and accommodating to the contour of said receptacle to force the material of the skirt into intimate contact with said receptacle.

12. In an apparatus for applying a closure cap having a depending skirt to the mouth of a receptacle, capping tools, said tools being singly mounted for movements in substantially different levels transversely to the receptacle to yieldingly press different longitudinal sections of the skirt against said receptacle, one of said tools being developed as a spinning tool and operative to move progressively along the receptacle at a right angle to threads formed on said receptacle, the transverse and progressive movement of said one tool being independent of any other of said capping tools to force the material of the skirt into intimate contact with said threads.

13. The method of applying a closure cap to a receptacle having an externally threaded top, which comprises placing a skirted cap on the receptacle, progressively spinning a screw thread on the cap skirt beginning the thread at the lower and completing it at the upper threaded portion of the receptacle and simultaneously spinning a lower portion of the cap skirt into intimate contact with the receptacle below a rim of said receptacle with a constant and smooth pressure until the spinning of the screw thread is finished.

14. In an apparatus for applying a closure cap having a depending skirt to the mouth of a receptacle, a pair of capping tools, said tools being mounted for movements at substantially different levels transversely to the receptacle to yieldingly press different longitudinal sections of the skirt against said receptacle, one of said tools being operative to move subsequently to the other tool transversely towards the receptacle and thereafter longitudinally of the receptacle relative to said other tool at a range of action beyond that of said other tool to progressively force the material of the skirt into intimate contact with the receptacle.
